BY Victor J. Evans

ATTORNEY

UNITED STATES PATENT OFFICE.

LOBE DWIGHT, OF KANSAS CITY, KANSAS.

DESIGN FOR A GRAVE PROTECTOR.

Application filed January 11, 1922. Serial No. 163. Term of patent 14 years.

To all whom it may concern:

Be it known that I, LOBE DWIGHT, a citizen of the United States of America, residing at Kansas City, in the county of Wyandotte and State of Kansas, have invented a new, original, and ornamental Design for a Grave Protector, of which the following is a specification, reference being had to the accompanying drawings, forming a part hereof.

The figure is a perspective view showing my new design.

I claim:

The ornamental design for a grave protector as shown.

LOBE DWIGHT.
